NONREFILLABLE BOTTLE

Samuel G. Conkling, Brooklyn, N. Y.

Application November 20, 1934, Serial No. 753,833

8 Claims. (Cl. 215—24)

This invention relates to new and useful improvements in non-refillable bottles, and it has for its object to provide a non-refillable bottle that will resist any attempt of refilling, and which 5 may be depended upon to function infallibly in operation, or use.

The present device constitutes a further improvement of my invention of a non-refillable bottle for which the U. S. Patent No. 2,013,726 has 10 been granted to me, September 10, 1935 and it has for its special object to provide means in connection with a bottle of the kind described, whereby an even and quick flow may be obtained of the contents of said bottle, in regard 15 to which still further constructional arrangement has been made, whereby the flow of liquid from the bottle may be adjusted and regulated.

As the construction of my invention is comparatively simple, the cost of manufacturing said 20 bottle with my devised features embodied therein should be proportionately low.

With the above and other objects in view, this invention consists of the novel features of construction, combination and arrangement of parts, 25 hereinafter fully described, claimed and illustrated in the accompanying drawing forming part of this specification, and in which similar characters of reference indicate corresponding parts in all views, and in which:—

30 Figure 1 is a side elevational view of part of a bottle neck, which has my device mounted therein, and shown in dotted lines.

Figure 2 is a vertical transverse section taken centrally through the neck and adjacent parts 35 of the bottle.

Figure 3 is a vertical central transverse sectional view taken through a cartridge-member, embodying and showing the main features and preferred construction of my invention without 40 the valve and its co-acting support, which also form indispensable parts of the latter; said cartridge-member being adapted for insertion into the neck of the bottle, forming an integral part, or unit, with said neck-portion, while leaving space for the insertion of the usual cork-stopper into the latter.

Figure 4 illustrates, in part, another vertical transverse sectional view taken through a cartridge member, the latter being in this view slightly 50 turned from the position shown in Figure 3, in order to illustrate the recess upon the side of, and additional cut-out portion in said cartridge-member, which features constitute part of my 55 new improvements.

Figure 5 is a horizontal sectional view of a part of a cartridge, showing the bore therein.

Figure 6 is a bottom view of the cartridge showing two cut-out portions.

Figure 7 is a vertical transverse sectional view 5 of a valve, adapted to be seated in and forming part of said cartridge.

Figure 8 is a modification of said valve, as the latter is shown herein, without the lever-arm.

Figure 9 is a vertical transverse sectional view 10 of a ring-member forming a seat for said valve, and constituting the bottom part of said cartridge-member; while

Figure 10 is a top plan view of said ring-member; and

Figure 11 is a top plan view of an annular substantially flat cork-member interposed between said ring-member and a shoulder formed at the juncture of the body of the bottle and the neck, and inside the latter at the entrance to said 20 body.

Referring more particularly to the drawing, 10 indicates the body of a bottle; while 11 indicates the neck formed integral therewith. The body and neck of the bottle, as well as the other parts hereinafter mentioned and associated with the former, while preferably made of glass, may however, be made of any suitable material, and of any convenient shape.

In the neck portion 11 is seated a cartridge-member 12 secured to the latter in any suitable manner, for instance by means of a cementing process, and said cartridge-member is made to form an integral part with said neck. The cartridge-member, when properly positioned in the neck of a bottle, will rest with its co-acting parts, which latter will be described hereinafter in detail, upon a shoulder 13 formed upon the neck, while at the top of the latter space is left for the insertion of the usual cork-stopper 14.

The cartridge-member 12 comprises an upper solid part, or section 15, formed with a longitudinal bore, or passage therein; said bore may be of a straight, tortuous, or any suitable form. The section 15 is at its lower end formed with a somewhat semi-spherical reduced portion, or chamber 17, registering with the said tortuous passage 16. The said section 15 has upon its wall 18, and extending into the chamber 17, been formed with a small oblong recess 19 adapted to receive a pivotally operating arm 20 of a valve 21 therein.

Approximately opposite the recess 19, the wall of the chamber 17 has been formed with a small lug 22, or it may be small projections as shown 55

especially in Figure 6, for the purpose of preventing a too far upward movement of the valve 21, when tilting the bottle for the purpose of pouring out the contents of the latter. The section 15 is further at its lower end provided with a flange 25 adapted to seat and snugly fit a valve-supporting ring, or member 26, thus making said cartridge-member, including its associated parts, present a complete unit ready for insertion into the neck of a bottle.

The valve 21, which is constructed with a central depression therein, may or may not, as shown in the Figures 7 and 8, respectively, be formed with a pivotally operating arm 20, which arm, in the event that the valve is formed with the latter, will rest in the recess 19 in the wall of the chamber 17, thereby securing the facilities for the regular, proper, and infallible functioning of the said valve in operation, that is, in the use of the bottle; said arm, when employed, terminates in a beaded end portion to facilitate the pivotal turning of the valve.

The ring 26, above referred to, is formed with an upwardly extending rim 27, adapted to seat the valve 21, as the flange 28 upon the latter forms a tight joint with said rim, when the valve 21 is seated upon said ring-member 26 in the upright position of a bottle.

The said ring-member 26 is formed with a horizontal annular edge-portion 29, below the rim 27, for the purpose of engaging the section 15, as the said annular edge-portion 29 fits closely within the flange 25 upon the section 15 of the cartridge-member.

The lower, or narrower part 30 of the ring-member 26 is made to receive, or engage a substantially flat annular cork-member, or washer 31, which is seated upon and abutting said ring-member, the said cork-member resting in turn upon the shoulder 13 at the lower end of the neck of the bottle.

However modifications may well be made in the construction of the said ring-member, while in like manner arrangements may be made, whereby to omit the said cork-member.

As an additional feature of great importance in regard to my invention, the member 15 has been provided with a second cut-out portion 32, like the one shown at 19, which cut-out portion 32 terminates in an elongated recess 33 extending a short distance upward in the side of said member 15, and close to the neck 11 of the bottle, as shown in Figure 4, and in Figure 1 in dotted lines.

The bottle neck has a small perforation 34 formed therein, in line with the upper part of said recess 33, and high enough positioned in the neck of the bottle to prevent any tampering with the valve through said aperture.

The said arrangement serves to facilitate a substantial elimination of the vacuum in the bottle, when it is desired to dispense the contents of the latter, thereby securing a quick and even flow of said contents.

It will thus clearly appear that by assembling the parts, shown herein, in the manner described, all that is necessary to apply said device to a bottle is to lower the cartridge-member into the neck of the bottle until it rests with the cork washer upon the shoulder of said neck; provisions being simultaneously made, whereby to make said member an integral part of the bottle.

The operation thus described naturally is done, when the bottle has been filled with its contents, and the usual cork-stopper is thereupon inserted to close the top of the neck of the bottle.

It may be desirable to have a ball-shaped member or valve positioned within the body of the bottle, or "wild" within the latter, so that when the bottle is in an inverted position, said ball will fall into place at the bottom of the valve seat, thereby closing the outlet through the latter, and thus preventing the withdrawal of vacuum from said bottle in an attempt to refill the latter. The use of such ball will not, however, interfere with the pouring out of the contents of the bottle governed by my hereinbefore described device. Thus when the bottle is inverted, the ball member 37, shown in Figure 12, moves forward and seats itself back of the valve seat in the neck of the bottle, thereby acting as a second closure member.

It is obvious that changes may be made in the form, construction and arrangement of the several parts, as shown, within the scope of the appended claims, without departing from the spirit of the invention, and I do not therefore wish to limit myself to the exact construction and arrangement shown and described herein.

What I claim, as new and desire to secure by Letters Patent of the United States, is:—

1. In a device of the class described, a bottle having a body portion and a neck integral therewith, said neck being formed with a shoulder inside thereof and at the entrance to the body of the bottle, a cartridge-member mounted in said neck and made to form an integral part therewith, a passage through said cartridge-member and a chamber formed at the bottom of the latter, a valve provided with a short arm and reciprocatingly arranged in said chamber, the cartridge-member being formed with a cut-out portion for accommodating the arm of said valve in the reciprocating movement of the valve, said cartridge-member having in its side a second cut-out portion terminating in a recess, the neck of the bottle proper being formed with a perforation therein, adapted to co-act with said latter recess in eliminating the vacuum from the bottle.

2. In a device of the class described, a bottle having a body portion and a neck integral therewith, said neck being formed with a shoulder inside thereof and at the entrance to the body of the bottle, a cartridge-member mounted in said neck and made to form an integral part therewith, a passage through said cartridge-member and a chamber formed at the bottom of the latter, flanges upon the lower end of said cartridge-member and a valve supporting ring engaged by said flanges, a valve seated upon said ring, said valve having a short arm and being reciprocatingly arranged in said chamber, the cartridge-member being formed with a cut-out portion for accommodating the arm of said valve in the reciprocating movement of the latter, said cartridge-member having in its side a second cut-out portion terminating in a recess, the neck of the bottle proper being formed with a perforation therein adapted to co-act with said latter recess in eliminating the vacuum from the bottle.

3. In a device of the class described, a bottle having a body portion and a neck integral therewith, said neck being formed with a shoulder inside thereof and at the entrance to the body of the bottle, a cartridge-member mounted in said neck and made to form an integral part therewith, a passage through said cartridge-member and a chamber formed at the bottom of the latter, a valve provided with a short arm and reciprocatingly arranged in said chamber, the cartridge-member being formed with a cut-out

- portion for accommodating the arm of said valve, lugs formed upon the cartridge-member and extending inside said chamber approximately opposite said cut-out portion for limiting the reciprocal movement of the valve, said cartridge-member having in its side a second cut-out portion terminating in a recess, the neck of the bottle proper being formed with a perforation therein, adapted to co-act with said latter recess in eliminating the vacuum from the bottle.
4. In a device of the class described, a bottle having a body portion and a neck integral therewith, said neck being formed with a shoulder inside thereof and at the entrance to the body of the bottle, a cartridge-member mounted in said neck and made to form an integral part therewith, a passage through said cartridge-member, and a chamber formed at the bottom of the latter, a valve provided with a short arm and reciprocatingly arranged in said chamber, the cartridge-member being formed with cut-out portions in the side thereof and through the latter, the neck of the bottle being made with a perforation therein substantially opposite one of said cut-out portions and adapted to co-operate with the latter, whereby to relieve the vacuum in the bottle in pouring out the contents of the latter.
5. In a device of the class described, a bottle having a body portion and a neck integral therewith, said neck being formed with a shoulder inside thereof and at the entrance to the body of the bottle, a cartridge-member mounted in said neck and made to form an integral part therewith, a passage through said cartridge-member, and a chamber formed at the bottom of the latter, a valve provided with a short arm and reciprocatingly arranged in said chamber, the cartridge-member being formed with cut-out portions in the side thereof and through the latter, the neck of the bottle being made with a perforation therein, the cartridge being formed with a slightly reduced portion adjacent the inside of the bottle neck, said reduced portion connecting the perforation in the bottle neck with one of the aforesaid cut-out portions in the cartridge, whereby to permit an inlet of air for relieving the vacuum in the bottle in pouring out the contents of the latter.
6. In a device, as claimed in claim 1, wherein the valve seat is made with sides tapering towards its center, and a ball member loosely disposed within the body of the bottle and adapted to snugly rest on the lower tapering surface of said valve seat, when the bottle is in an inverted position, thereby preventing the withdrawal of vacuum from the bottle in said latter position.
7. In a device, as claimed in claim 1, wherein the valve seat is made with sides tapering towards its center, and a ball member loosely disposed within the body of the bottle and adapted to snugly rest on the lower tapering surface of said valve seat, when the bottle is in an inverted position, thereby forming a double valve combination in said bottle.
8. In a device of the class described, a bottle having a body portion and a neck integral therewith, said neck being formed with a shoulder inside thereof near the body of the bottle, a cartridge-member mounted in said neck and made to form an integral part therewith, said cartridge-member having a passage therethrough and a chamber at the bottom thereof, a valve provided with a short arm and reciprocatingly arranged in said chamber, the cartridge-member being formed with cut-out portions in the side thereof terminating in a recess therein, the valve seat being made with sides tapering towards its center, and a ball member loosely disposed within the body of the bottle and adapted to snugly rest on the lower tapering surface of said valve seat, when the bottle is in an inverted position, whereby to prevent the withdrawal of air from the bottle in said latter position.

SAMUEL G. CONKLING.
